UNITED STATES PATENT OFFICE

JOHN B. KEMP, OF RIDGEWOOD, NEW JERSEY, ASSIGNEE TO CLARK LOOSE LEAF MANUFACTURING COMPANY, A CORPORATION OF NEW YORK

PAD HOLDER

Application filed August 9, 1930. Serial No. 474,121.

This invention relates generally to pad holders adapted to retain a calendar ring or other memoranda in position, and more particularly to an arrangement for holding a group of superposed members in proper relation and in angular position with reference to the supporting surface.

The present invention is an improvement over my copending application, Serial No. 426,547, filed September 7, 1930, and provides in addition to all of the objects provided in the aforementioned application, the provision of improved securing means for the pad holding and aligning bolts.

It is thus among the objects of the invention to provide improved means for receiving and securing pad holding bolts in conjunction with the pad supporting surface.

Another object is to provide bolt receiving means associated with the base for threadedly receiving the bolt therethrough without threading the base or otherwise directly imparting strains from the bolt thereto.

Another object is to provide a bolt securing attachment for a pad holding base in which the bolt engagement is independent of leg supports and whereby the legs may be moved independently and without respect to the location of the bolts.

Other objects and advantages will appear as the nature of the improvements is better understood, the invention consisting substantially in the novel arrangement and co-relation of instrumentalities herein fully described, and illustrated in the accompanying drawings, wherein similar reference characters are used to describe corresponding parts throughout the several views, and then finally pointed out and specifically defined and indicated in the appended claims.

The disclosure made the basis of exemplifying the present inventive concept suggests a practical embodiment thereof; but the invention is not to be restricted to the exact details of this disclosure, and the latter, therefore, is to be understood from an illustrative, rather than a restrictive, standpoint.

The inventive idea involved is capable of receiving a variety of mechanical expressions,

only a few of which, for the purposes of illustration, are shown in the accompanying drawings, in which—

Fig. 1 is a view partially in section of one form of the present invention in position on a disc, and taken on the line 1—1 of Fig. 2.

Fig. 2 is an end elevation of the device shown in Fig. 1.

Fig. 3 is a detailed section taken on line 3—3 of Fig. 2.

Fig. 4 is a view similar to Fig. 3 showing the supporting leg in folded position.

Fig. 5 is a detailed view of the bolt engaging element.

Fig. 6 is a view similar to Fig. 3 of a modified form of the invention, and

Fig. 7 is a detailed view of the modified bolt receiving element.

In the drawings, 1 represents a pad which, for the purpose of illustration, is a calendar pad, the pad resting on a base 2 and being apertured as at 3 to receive combining screws 4 therethrough. In previous forms of the present invention the combining screws were adapted for threaded engagement into heads 5 of standards or legs 6, which are pivotally carried by the under side of the base by reception of the heads 5 within sockets 7 carried by the base. While the general structure of the previous devices is herein illustrated as a preferred embodiment, the structure involving the use of caps 8 and spring 9 which are adapted to retain the standards in their adjusted position, one side of the socket being open to permit their folding as indicated in Fig. 4, the invention departs from the prior teaching by the provision of a screw or bolt receiving plate 10 which in the form of the invention shown in Fig. 3 is mounted on the upper surface of the base 2 and secured over the aperture 11 of the base by the socket securing rivets 12.

The element 10 as shown in Fig. 5 is elongated, its ends being apertured as at 13, to receive the rivets 12 therethrough and its center being apertured and internally threaded to provide a boss 14 for threadedly engaging the lower end of the screw 4. As a manufacturing expedient, the element 10 is herein shown as having its central portion extruded and in-

ternally threaded, it being understood however, that the invention is not confined to this mechanical expedient.

The head 5 of the leg or standard 6 is not internally threaded as in accordance with prior practice and is apertured with a bore greater than the diameter of the screw. The screw when the pad is full does not extend into the standard head 5 and permits the standard to be freely moved but properly secures the pad by engagement in the boss 14 of the element 10. Thus the device may be shipped with the legs folded and the pad firmly secured upon the base. After considerable thickness of the sheets of the pad is removed, downward screwing of the bolting provides for the entrance of its lower end within the head 5 to prevent accidental folding of the standard.

By this form of the invention it will be seen that the pad is secured independently of the standard and strains are directed not directly to the base which may preferably be formed of paper material, but are carried through the element 10 to be distributed through the rivets 12, thus eliminating danger of disrupting the threaded connection.

By referring more particularly to that form of the invention shown in Figs. 6 and 7, it will be seen that the invention comprehends the use of securing screws 4 out of alignment with the standard 6. In this instance the screw receiving element, as shown in Fig. 7, is indicated by the numeral 20 and has apertures 21 adapted to receive the socket securing rivets 12. The element 20, however, extends beyond one of the apertures 12 and has an extruded end boss 22 which is adapted to be received within an aperture 23 of the boss 2, and thus provides for the alignment of the screw 4 out of the axial path of the standard 6. In the use of the device, regardless of how thin the pad becomes through removal of sheets, the screw 3 will never extend downwardly to interfere with the folding of the standard.

In both forms of the invention, it will be seen that a novel and simple structure is provided, by which a rigid screw receiving boss is provided, so arranged as to prevent mutilation of the boss by engagement of the screw therewith, and also arranged to be secured independently of the standard. These features provide for free folding of the standard without regard to the position of the screw and provide an inexpensive structure particularly designed to meet the demands of economic manufacture.

In accordance with the provisions of the patent statute, I have described the principle of my invention, a practical embodiment thereof, but I desire it understood that my invention is not confined to the particular form of device herein shown and described, the same being merely illustrative, and that the inven-

tion can be carried out in other ways without departing from the spirit of my invention, and, therefore, I claim broadly the right to employ all equivalent instrumentalities coming within the scope of the appended claims, and by means of which the objects of my invention are attained, and the new results accomplished, as herein set forth, as it is obvious that the particular embodiments herein shown and described are only some of many that can be employed to attain these objects and accomplish these results.

Having thus described my invention, what I claim as new and desire to secure by Letters Patent, is:

1. A pad holder including a base, standards associated therewith for supporting the base in inclining position with respect to a supporting surface, a pad carried by the base, a securing screw extending through said pad and threaded means carried by the base independent of the standards for threadedly receiving the screw for retaining the pad on the base, said means being secured to the base by rivets securing therewith the standard to the base.

2. A pad holder including a base, standards associated therewith for supporting the base in inclining position with respect to a supporting surface, a pad carried by the base, a securing screw extending through said pad and threaded means carried by the base independent of the standards for threadedly receiving the screw for retaining the pad on the base, said means being secured to the base by rivets securing therewith the standard to the base, said means comprising an elongated plate bearing an internally threaded boss for receiving the screw.

3. A pad holder including a base, standards associated therewith for supporting the base in inclining position with respect to a supporting surface, a pad carried by the base, a securing screw extending through said pad and threaded means carried by the base independent of the standards for threadedly receiving the screw for retaining the pad on the base, said means being secured to the base by rivets securing therewith the standard to the base, said means comprising an elongated plate bearing an internally threaded boss for receiving the screw, said boss being aligned on said base in axial registration with the standard.

4. A pad holder including a base, standards associated therewith for supporting the base in inclining position with respect to a supporting surface, a pad carried by the base, a securing screw extending through said pad and threaded means carried by the base independent of the standards for threadedly receiving the screw for retaining the pad on the base, said means being secured to the base by rivets securing therewith the standard to the base, said means comprising an elongated

plate bearing an internally threaded boss for receiving the screw, said boss being aligned on said base in axial registration with the standard, said standard being apertured to receive the screw therein.

5. A pad holder including a base, standards associated therewith for supporting the base in inclining position with respect to a supporting surface, a pad carried by the base, a securing screw extending through said pad and threaded means carried by the base independent of the standards for threadedly receiving the screw for retaining the pad on the base, said means being secured to the base by rivets securing therewith the standard to the base, said means comprising an elongated plate bearing an internally threaded boss for receiving the screw, said boss being arranged out of alignment with the standard.

10 6. A pad holder including a base, standards associated therewith for supporting the base in inclining position with respect to a supporting surface, a pad carried by the base, a securing screw extending through said pad and threaded means carried by the base independent of the standards for threadedly receiving the screw for retaining the pad on the base, said means being secured to the base by rivets securing therewith the standard to the base, said means comprising an elongated plate bearing an internally threaded boss for receiving the screw, said boss being arranged beyond the rivet securing of the element to provide for reception of the screw out of alignment with the standard.

This specification signed this 4th day of August, 1930.
